UNITED STATES PATENT OFFICE.

FRANK R. SPEAR, OF CHICAGO, ILLINOIS.

COMPOSITE BRAKE-SHOE.

SPECIFICATION forming part of Letters Patent No. 678,139, dated July 9, 1901.

Application filed October 29, 1900. Serial No. 34,747. (No specimens.)

To all whom it may concern:

Be it known that I, FRANK R. SPEAR, of Chicago, Illinois, have invented certain new and useful Improvements in Composite Brake-Shoes, of which the following is a specification.

My invention has for its object to produce a composite brake-shoe in which the wearing-face is provided with a composition more durable and efficient than has been heretofore employed, to my knowledge, and this I secure by the employment of coal-tar or coal-tar pitch as the essential ingredient of my composition.

Composite brake-shoes have been patented, and many of them experimented with and used to a greater or less extent, in which the wearing-face is provided with masses of compositions of various ingredients, generally consisting, however, of some metallic substance in a state of fine mechanical division in conjunction with a binder, such as asphaltum and the like. The chief trouble which has occurred heretofore in the use of brake-shoes having compositions of this character has been that the composition is subject to disintegration in service and soon falls out of the pocket or cavity formed in the shell or shoe. This disintegration is probably due to the excessive heat generated by the extreme pressure of the brake-shoe upon the wheel, this extreme pressure, particularly at a high rate of speed, being sufficiently great to generate a low red heat.

I employ as the chief ingredient of the composition the residuum of destructive distillation of coal—for example, in the production of coke and coal-gas—which residuum is a thick viscid substance commonly known as “coal-tar.” This coal-tar I prefer to employ in the more refined condition, which is brought about by removing therefrom some of its constituents, such as the analin colors, in which more refined condition it is known as “coal-tar” pitch. I have found that either of these substances, or, in other words, this substance in either condition above described, when mixed with some of a number of well-known ingredients commonly used for this purpose, will give a superior composition for use in brake-shoes. The other ingredients which I prefer

to employ are asbestos and iron-borings or iron-filings.

My composition may be composed of these several ingredients in the following proportions: iron-borings, two hundred pounds; asbestos, twenty-five pounds, and coal-tar or coal-tar pitch, twenty-five pounds. In compounding these ingredients the asbestos in the fibrous form is mixed with the iron-borings, and the coal or coal-tar pitch is heated and added to the mixture. The mass is thoroughly worked, and while it is still hot it is charged into the pockets or cavities of the shell of the brake-shoe under suitable pressure, where it solidifies quickly.

In the accompanying drawings is shown a brake-shoe of the general class or kind to which my invention applies.

Figure 1 is a face or plan view; Fig. 2, a side elevation, and Fig. 3 a cross-section.

The body or shell of the shoe is marked A, and it has one or more pockets or recesses in its face, the cross-sectional form of the pocket or recess preferably being dovetailed. B represents the composition mass within such pocket.

The form of the brake-shoe is immaterial, and the form of the recesses or pockets may be varied at pleasure.

In use I have found that this composition does not disintegrate under any heat produced by the friction of the shoe upon the car-wheel. Coal-tar or coal-tar pitch not only acts as a binder in mixing the composition, but under the action of the heat due to friction it apparently is not affected throughout the mass, but only upon the surface, and such surface under the influence of the heat and pressure becomes hard and glossy, but to the touch appears to possess in low degree the quality of lubrication. It does not under heat and pressure become fluid or even plastic, but particles in the form of soot may be removed from the surface after it has been subjected to use. Tests have shown that the mass of the composition does not become heated throughout, and it is to this characteristic that I attribute the lasting quality of the material, since the major portion of the mass apparently is unaffected by service and is only

worn as the wear on the face of the shoe progresses. I have found this composition to possess the requisite frictional qualities in high degree.

5 While I have indicated a composition containing certain ingredients, I do not intend to limit my invention to the described ingredients nor to the exact proportions stated. The qualities and the purpose of using the 10 iron-borings and asbestos are well known and one or both of them may be omitted, provided that other substances be substituted serving the same or substantially the same purposes in the composition. For example, the asbestos 15 may be substituted by some other ingredient of a fibrous nature having the property of binding the mass together and preferably capable of resisting wear, and the iron particles may be any form of that metal in a fine 20 state of division, or other metal in like state may be employed.

One result of the wear of the composition due to the friction, which is highly important, is the coating of the wheel-surface with a 25 skin of the material of the composition itself, and as the composition wears down the surface of the mass gives off a fine substance in a form which is most nearly described by the term "soot," being a fine powder having an 30 adhesive quality, and this fine adhesive powder will coat the metal surface of the shoe and the wheel-rim, and this coating protects the wheel and shoe in their contact with each

other, and also protects the wheel in its contact with the rail and minimizes the wear of 35 the wheel to an appreciable extent.

While I have described the detritus produced by wear as having a lubricating quality, it will be understood that said quality does not detract from the efficiency of the 40 shoe to produce braking friction upon the wheel, but, on the contrary, it materially adds thereto. The lubricating quality of the composition is also such as to prevent the locking 45 of the shoe to the wheel under excessive pressure, as in making an emergency stop. It is well known that brake-shoes are sometimes forced into contact with the wheel under such pressure as to positively lock the surfaces together, thereby causing the sliding of the 50 wheels, which is destructive alike to the wheel and to the rail. My composition reduces the danger of the occurrence of this interlocking of the shoe and wheel to a minimum.

I claim—

1. A composition for brake-shoes having as an essential ingredient coal-tar or coal-tar pitch, finely-divided particles of metal and a fibrous substance, substantially as described.
2. A composition for brake-shoes composed 60 essentially of comminuted iron, asbestos and coal-tar, substantially as described.

FRANK R. SPEAR.
